UNITED STATES PATENT OFFICE.

WILLIAM M. BYER, OF JERSEY CITY, NEW JERSEY.

LIQUID-DISPENSING DEVICE.

No. 924,887.

Specification of Letters Patent.

Patented June 15, 1909.

Application filed December 26, 1908. Serial No. 469,393.

To all whom it may concern:

Be it known that I, WILLIAM M. BYER, a citizen of the United States of America, and a resident of Jersey City, New Jersey, have 5 invented certain new and useful Improvements in Liquid - Dispensing Devices, the principles of which are set forth in the following specification and accompanying drawings, which disclose the form of the invention which I now consider to be the best of 10 the various forms in which the principles of the invention may be embodied.

This invention relates to liquid - feeding devices, as for the purpose of dispensing 15 liquid soap for toilet purposes.

The object is a device possessing the improvements hereinafter specified, which shall be economical and convenient in operation, cheap in construction, easy of assemblage, 20 compact in form and regular and efficient in its action of feeding predetermined quantities of liquid.

Of the drawings, Figure 1 is a vertical central section, and Fig. 2 a front elevation.

25 As shown in Fig. 1, the glass reservoir A for the liquid to be dispensed has a metal casing B and contains a piston-cylinder C with contained piston G, the cylinder or chamber C having a slot D substantially 30 through its length from a point just below the upper limit of the play of the piston, for the purpose of utilizing the cylinder-interior above the piston as additional available reservoir-space for the liquid. When 35 depression of piston G, as shown, causes an out-flow of liquid from cylinder C, the liquid passes through a pipe I constituting an intermediate riser-passage, to a gravity feed and splash eliminator to be described. If

40 the liquid were forced exterior to the entire apparatus directly by the piston pressure, it would be emitted with such force as to splash or spatter against the hand of the person held in position below the bottom outlet Q 45 to receive it, in a wasteful as well as an annoying manner. But here, not only is the riser-passage I always filled with liquid by the automatic operation of a check-valve J, such as the common conical construction, 50 but also, it is forced out of passage I into a gravity outlet K¹ constructed with an enlargement or hopper K with which passage I communicates, which serves to take up the splash and eliminate its occurrence outside

the apparatus, by acting momentarily as a 55 reservoir which has a splash - eliminating function as to the final exit of the liquid. The liquid flows from K downward through K¹, gently by gravity to and through the final outlet Q, and not under the piston-pressure, as Q and K¹ furnish free upward access 60 for air, and K may be open to the air in the upper part of the reservoir. This permits the hand of the user to receive the predetermined amount of liquid which flows out 65 in a gentle stream without spattering or splashing. If desired, the cylinder C may communicate directly with K, either in the illustrated location of the latter, (by reversing the direction of piston-action), or with 70 the latter located below the lower end of C, with the direction of piston-action shown. The riser-passage I has, however, a most useful function in the illustrated construction and arrangement, and the latter in all its 75 aspects, is the preferred embodiment of the invention. The pipe K¹ may extend down so as to discharge directly into outlet Q. The relative construction of the parts, as well as their relative arrangement, is immaterial, 80 provided that the described function is executed.

The advantage of retaining the function of the piston or its equivalent is to dispense a predetermined quantity of liquid. A cap 85 F is provided as shown, having a downward projection F¹ fitting down into the top of the cylinder C and secured thereto. The casing-top O may also be secured to the cylinder C. Reciprocable in cap F, F¹ is a bushing F¹ secured to the upper part of piston-rod E. A handle or push button P is secured to the upper end of piston-rod E. Bushing F¹ has a lower flange-portion F² 90 fitting against the lower surface of cap-portion F¹, this flange being engaged by the upper end of helical spring N. The lower end of the spring rests on a collar M which is secured, as by soldering, to the inside of cylinder C. Thus the spring normally acts 95 upwardly against flange F² to hold piston G in position for operation, the cylinder below the piston being filled with liquid of a predetermined quantity dependent upon the location of the lower end of slot D. When 100 button P is depressed to compress the spring, the piston-rod and piston are also depressed to force the liquid into pipe I, opening 105

check-valve J upwardly to force liquid throughout the length of said pipe. When the hand pressure on button P is removed, the liquid in the upper part of pipe I closes 5 check-valve J downwardly, and the spring automatically raises piston G, the liquid above G being free to be forced thereby through the entire submerged upper portion of the long slot D, to mingle with the liquid 10 in the main reservoir outside of cylinder C, whence it reenters said cylinder but below the piston and through the lower part of slot D. This keeps pipe I filled with liquid up 15 to the check-valve J, and, as the latter keeps the portion of the pipe I above it continually filled with liquid, irrespective of the liquid-level in reservoir A, the next operation of piston G will force into K an amount of the liquid which stands in the upper part of 20 pipe I which corresponds with the above-stated predetermined feed. Check-valve J may be operatively located approximately or substantially on a level with the lower face of piston G, so that by means of slot D, 25 pipe I will be filled up to the check-valve as long as there is enough liquid in the main reservoir to reach the lower face of the piston. The cap F may be secured to metal cover O, or as shown, C, to which F is secured, 30 may be secured to O, so that cylinder C and pipe I and their interior parts may be all removed at once, in case the pipe I is separable from K as shown.

The filling-inlet S in casing top O may 35 contain at its lower part a float-valve U to prevent overflow in filling. If desired, the gravity outlet passage may be through a pipe K¹ located in a space between A and B; but any suitable means may be employed. The 40 top casing part O, as well as the bottom casing part L, may be, screwed as shown, removably attached to main part B; part L having an internal flange L¹ serving as a support for glass reservoir A. Main casing- 45 part B is cut away in front, as shown in Fig. 2, to permit inspection of interior of glass reservoir A; or it may be complete if the reservoir is not transparent. The entire apparatus may be laterally supported from 50 the wall, as by bracket-jaws R; or the standard T may carry the bracket R.

I claim:—

1. In a liquid-feeding apparatus, the combination with a liquid-reservoir, of a piston- 55 chamber therein, a slot in the piston-chamber, a piston normally held above the lower end of the slot, a riser-passage communicating with the piston-chamber, a check-valve in the riser-passage at substantially the 60 level of the normal position of the piston, and a gravity outlet communicating with the riser-passage and constructed to act as a temporary reservoir to eliminate the liquid-splash.

2. In a liquid-feeding apparatus, the com-

bination with a liquid-reservoir, of a piston to force the liquid therein toward the exterior thereof, a riser-passage to receive the liquid flowing under the piston action, and a gravity outlet receiving the liquid from the riser-passage and constructed to act as a temporary reservoir to eliminate the liquid-splash caused by the piston action.

3. In a liquid-feeding apparatus, the combination with a liquid-reservoir, of a piston to force the liquid therein toward the exterior thereof, a riser-passage to receive the liquid flowing under the piston action, a check-valve in the riser-passage to keep the latter full of liquid, and a gravity outlet receiving the liquid from the riser-passage and constructed to act as a temporary reservoir to eliminate the liquid-splash caused by the piston action.

4. In a liquid-feeding apparatus, the combination with a liquid-reservoir, of a piston to force the liquid therein toward the exterior thereof, of a piston-cylinder in the reservoir extending substantially from top to bottom thereof and being partially open substantially throughout its length and providing additional available reservoir-space, a riser-passage communicating with the piston-cylinder to receive the liquid flowing under the piston action, and a gravity outlet receiving the liquid from the riser-passage and constructed to act as a temporary reservoir to eliminate the liquid-splash caused by the piston action.

5. In a liquid-feeding apparatus, the combination with a liquid-reservoir, of a piston to force the liquid therein toward the exterior thereof, a riser-passage to receive the liquid flowing under the piston action, and a temporary or splash-eliminating reservoir 100 communicating with said riser-passage and having a gravity outlet.

6. In a liquid-feeding apparatus, the combination with a liquid reservoir, of a piston to force the liquid therein toward the exterior thereof, a riser-passage to receive the liquid flowing under the piston action and a gravity outlet passage formed with an enlargement serving as a splash-eliminating 110 temporary reservoir.

7. In a liquid-feeding apparatus, the combination with a liquid-reservoir, of a piston to force the liquid therein toward the exterior thereof, a piston-cylinder in the reservoir extending substantially from top to bottom thereof and being partially open substantially throughout its length and providing additional available reservoir-space, a riser-passage a check-valve in the riser-passage to keep the latter full of liquid, and a gravity 120 outlet receiving the liquid from the riser-passage and constructed to act as a temporary reservoir to eliminate the liquid-splash caused by the piston action.

8. In a liquid-feeding apparatus, the com-

bination with a liquid reservoir, of a piston-cylinder inside the reservoir, a riser-passage communicating with the piston-cylinder, a gravity outlet receiving the liquid and a piston in the piston-chamber for forcing liquid therefrom into the riser-passage.

5 from the riser-passage and constructed to act as a temporary reservoir to eliminate the liquid-splash caused by the piston action,

WILLIAM M. BYER.
